UNITED STATES PATENT OFFICE.

AURIN WOOD, OF WORCESTER, MASSACHUSETTS, AND GEORGE PLACE, OF NEW YORK, N. Y.; SAID WOOD ASSIGNOR TO CORNELIUS VAN BRUNT, OF NEW YORK, N. Y.

CENTERING-MACHINE.

SPECIFICATION forming part of Letters Patent No. 363,874, dated May 31, 1887.

Application filed October 26, 1885. Serial No. 181,020. (No model.)

To all whom it may concern:

Be it known that we, AURIN WOOD, a citizen of the United States, residing at Worcester, in the county of Worcester and State of Massachusetts, and GEORGE PLACE, a citizen of the United States, residing in the city, county, and State of New York, have invented certain new and useful Improvements in Centering-Machines, of which the following is a full, clear, and exact description, accompanied by drawings representing a centering-machine embodying our invention, and in which—

Figure 1 shows a front elevation; Fig. 2, a sectional view on line X X, Fig. 4. Fig. 3 is a top view. Fig. 4 is an end view. Fig. 5 is a transverse sectional view on line S S, Fig. 1; and Fig. 6 shows a portion of the under side of one of the saddles G G'.

Similar letters refer to similar parts in the several views.

Our invention relates to certain improvements in machines for "centering" the ends of shafts, spindles, or bars of metal which are to be turned; and it consists in the use of two centering-spindles to which a simultaneous longitudinal movement is given by which both rotating drills are carried at the same time to the ends of the bar to be centered, in the construction and arrangement of the mechanism for so moving the centering-spindles, in devices for clamping the shaft, which are adjustable along the bed of the machine, in an adjustable head by which shafts of varying lengths may be centered, and in the construction and arrangement of the several parts, as hereinafter described.

A A is the frame or bed of the machine, on which are mounted the two heads B and B'. The head B is attached to the bed and the head B' has a sliding motion along the way a a, permitting the space between the heads to be varied as longer or shorter shafts are to be centered, the head being fastened to the bed, when the machine is in operation, by a tightening-screw, a', which, passing through the gib a'' and entering the base of the head, serves to firmly clamp the head B' to the bed of the machine. The belt-pulleys C C' have long hubs, which form the bearings b b', held in the heads

B B', and through which the spindles D D' have a sliding motion, rotary motion being imparted to the spindles from the pulleys by means of the splines e e'.

The spindles D D' carry sleeves d d', with teeth on their under sides, and held between the shoulders d² and the nuts d³, and are prevented from turning by splines e e' in the heads B B'. Pinions f and f', turning on studs in the head B, connect the toothed sleeve d' with the rack E, sliding in a groove in the bed of the machine, and the pinions f², f³, and f⁴ connect the opposite end of the rack E with the toothed sleeve d.

A reciprocating sliding motion is given to the rack E by means of the pinion g on the shaft g', held in the head B, and having a lever, g², a motion of the rack E to the right carrying the sleeves d d' and their connected spindles D D' simultaneously toward each other, and the motion of the rack E to the left reversing the motion of the sleeves d d' and spindles D D'. Between the heads B B' we place the clamping-jaws F F' and F² F³, sliding in ways on the saddles G G' and actuated by the right and left hand screws H H', which are held in bearings g³ g⁴ on the saddles G G', and are operated by the cranks h h'. The sliding jaws hold the detachable blocks I, presenting the opposing re-entering rectangular faces i i, between which the shaft J to be centered is held.

The blocks I are readily removed and others substituted adapted to the different sizes of shafts. Upon the under sides of the saddles G G' are the cam-levers k k', turning upon studs l l' in the saddles and pressing against the shoe L, fitting the way a, so that a slight rotation of the cams will clamp the saddles G G' firmly on the way of the machine, allowing the position of the shaft-holding jaws to be changed at will. In case short pieces are to be centered, one pair of jaws will usually be sufficient.

When the movable head B' is to be adjusted for different lengths of shafts, the screw a' is loosened and the pinion f moved on its stud out of gear, allowing the head to be placed in the desired position on the way a a and again clamped by the screw a', and the pinion f put

in gear. The spindles are then separated by a motion of the lever g^2 . The shaft to be centered is placed between the opposing faces of the sliding jaws F , F' , F^2 , and F^3 , the rotation 5 of the right and left hand screws H H' bringing the jaws firmly against the sides of the shaft. The motion of the lever g^2 is then reversed and the spindles D D' carried toward each other, bringing the drills K K' in position to bore a "center" hole in both ends of the shaft J at the same time.

The axes of the spindles D D' are in alignment, and the jaws, which are brought in contact with the periphery of the shaft J at or near 5 its ends, hold the shaft in proper position to be "centered" by the action of the drills K K' .

What we claim as our invention, and desire to secure by Letters Patent, is—

1. The combination, with the rotating spindles, of sleeves provided with teeth, a rack sliding in ways, and pinions intermediate the rack and toothed sleeves, so the longitudinal motion of the rack will produce a simultaneous

sliding motion of the spindle toward or away from each other, as and for the purpose set 25 forth.

2. The combination, with the bed A and heads B B' , carrying the opposing drill-holding spindles D D' , of shaft-holding jaws adjustable on the bed of the machine and cam-levers 30 k k' , acting against the bed of the machine, as and for the purpose set forth.

3. The combination, with a pair of opposing drill-holding spindles having geared sleeves, of a sliding rack geared to the toothed sleeves by 35 intermediate pinions and a shaft geared by a pinion to the sliding rack, and having a hand-lever, as and for the purpose set forth.
